N. L. KEARNEY

PROTECTION SCREEN FOR AIRPLANE COCKPITS

Filed April 8, 1924

FIG. 1.

FIG. 2.

INVENTOR
Norman L. Kearney

BY

Robert H. Young, ATTORNEY

UNITED STATES PATENT OFFICE.

NORMAN L. KEARNEY, OF DAYTON, OHIO.

PROTECTION SCREEN FOR AIRPLANE COCKPITS.

Application filed April 8, 1924. Serial No. 705,006.

To all whom it may concern:

Be it known that I, NORMAN L. KEARNEY, a citizen of the United States, residing at Dayton, in the county of Montgomery and 5 State of Ohio, have invented certain new and useful Improvements in Protection Screens for Airplane Cockpits, of which the following is a specification.

This invention relates to a protection screen to serve as a guard in front of the instrument board in an airplane or other vehicle and prevent injury to the pilot in the event of a crash, it being found that in many instances casualties resulted merely due to 10 the pilot fracturing his skull by engaging projections on the instrument board such as a compass or ignition lever or the like, as he lunged forward at the instant of the crash.

The invention provides a screen preferably removably mounted in spaced relation to the instrument board so that free access can be had to the instruments in the operation of the plane, the screen being of a sufficiently large mesh that the instruments 15 are in clear view through the same.

In the description, reference is made to the accompanying drawing, in which:

Fig. 1 is a perspective view of the cockpit portion of an airplane fuselage showing a screen provided in front of the instrument board in accordance with my invention. 20

Fig. 2 is a longitudinal section on a reduced scale of the cockpit portion of the fuselage showing the relation of the screen to the instrument board.

The protection screen 10 may be made of any suitable material and is preferably made of a small mesh netting which enables a clear view of the instruments therebehind, 25 but which nevertheless is of a size which prevents injury to the pilot by preventing engagement with any of the instruments or controls located on the instrument board 11 in the event of a crash. There are usually

about ten or twelve instruments located on the instrument board most of which have portions projecting from the plane of the instrument board and have sharp edges which constitute quite a hazard when it is 30 considered that they are in direct line with the pilot's head, and may be struck as he is caused to lunge forward in the cockpit when the plane crashes. The screen 10 is conveniently provided with a frame 12 removably mounted in the fuselage in front of the instrument board. In Fig. 2 it is seen that

ample space is left between the screen and the instrument board permitting free access to the instruments and controls on the board. It is of advantage to have the screen removable in the event it becomes necessary to replace or repair any of the instruments or controls. It is apparent that aside from the function which the screen performs as a safety measure, it serves also as a protection 60 against possible injury to the instruments when work is being done on the plane.

I claim:

1. In a vehicle, the combination with the instrument and control board in front of operator which constitutes a hazard because liable to impact in the event of a crash, of a protective screen to prevent such impact spaced sufficiently from said board to permit free access thereto for manual manipulation 70 or adjustment thereof.

2. In an airplane cockpit the combination with the instrument board of a transverse screen in front of the same to be engaged before the instruments or controls on the board to avoid injury to the aviator in the case of a crash, and also to avoid injury to the instruments under other circumstances. 80

3. In an airplane cockpit, the combination with an instrument board of a framed screen 85 removably mounted in front of said board a sufficient distance away therefrom to permit free access to the instruments or controls on the board, the screen being of a size permitting a clear unobstructed view of the instruments and controls.

4. In an airplane cockpit, the combination with an instrument board, of a framed screen removably mounted in front of said board close enough to permit free access to the instruments and controls on the board, and a sufficient distance away that the expansion of the screen caused by an impact by the operator would be less than the distance of the screen from said board. 90

5. In an airplane cockpit, the combination with an instrument board of a framed screen removably mounted in front of said board a sufficient distance away therefrom to permit free access to the instruments or controls on the board, the screen being of small mesh so that the expansion of the same caused by an impact by the operator would be less than the distance of the screen from said board. 105

In testimony whereof I affix my signature. 110

NORMAN L. KEARNEY,
